United States Patent Office

Des. 185,482
Patented June 9, 1959

185,482

SHIRT FOLDING BOARD

Helen M. Ziegler, Wilton, Conn.

Application September 24, 1958, Serial No. 52,743

Term of patent 14 years

(Cl. D49—1)

FIG. 1

FIG. 2

FIG. 3

Fig. 1 is a perspective view of a shirt folding board embodying my new designs;

Fig. 2 is an elevation view taken from the top of Fig. 1; and

Fig. 3 is a side elevation view, thereof.

I claim:

The ornamental design for a shirt folding board, as shown.
